UNITED STATES PATENT OFFICE.

CHARLES A. HANSGEN AND JAMES R. COLEMAN, OF ROCK ISLAND, ILL.

CAR-COUPING.

SPECIFICATION forming part of Letters Patent No. 298,325, dated February 12, 1884.

Application filed October 19, 1883. (No model.)

To all whom it may concern:

Be it known that we, CHARLES A. HANSGEN and JAMES R. COLEMAN, of Rock Island, in the county of Rock Island and State of Illinois, have invented certain new and useful Improvements in Car-Couplers; and we do hereby declare that the following is a full, clear, and exact description of the invention, which will enable others skilled in the art to 10 to which it appertains to make and use the same, reference being had to the accompanying drawings, and to the letters of reference marked thereon, which form part of this specification.

15. Our improvements relate to that class of inventions known as "car-couplers," having for their object the provision of means whereby an automatic coupling of cars may be effected, and also to provide means for uncoupling the same without the necessity of going between the cars, thereby lessening the danger of accident to the operator.

20. To these ends the invention consists in such details of construction and combination of parts as will be hereinafter described, and distinctly pointed out in the claim.

25. Referring to the drawings, Figure 1 represents a top view of two cars as coupled by our device. Fig. 2 represents an inverted view 30 of two cars, showing in plan the construction and arrangement of our invention. Fig. 3 is a view in perspective of an end of a car wherein our improvements are embodied.

35. Reference being had to the letters marked thereon, A represents a car-body, to the under side of which and projecting beyond the end of, is arranged the coupling device.

40. B indicate the heavy frame-work of the bottom of the car, and b b are timbers, having secured thereto in suitable manner hangers or 45. brackets c c. Secured to the cross-piece at the forward end of the car is another bracket, C, which serves as a guide for the draw-bar as it is made to move laterally in effecting a coupling.

45. D represents the draw-bars, having heads d, which heads are designed to be of quite considerable vertical height, and project or branch off to one side of the draw-bar, thus forming 50 inner faces, which clasp together when the ears are coupled. It will be observed that the front face of said heads converge into a

mouth, d', having holes in its lips for the insertion of a link-pin when it is desired to simply employ the ordinary link-coupling. The inner 55 end of the draw-bar D terminates in a pin-like portion, on which is arranged a suitable buffer-spring, E. This spring works between two metal bars, e e', which are fitted on the smaller portion of the draw-bar transversely, 60 and whose ends project through the brackets c c. Normally this buffer-spring is expanded, and keeps the bars e e' apart.

F is a spring bearing against one side of the draw-bar, and working in a sleeve, f, secured 65 to the under side of the car in any suitable manner. This spring yields as the draw-bar is made to move laterally, and acts to restore it to thus effect the coupling.

G is a curved arm or lever, which is fulcrumed to the end of the car, the longer arm thereof working in a vertical guide, g, secured to the car at near the side, while its shorter arm curves or extends down through a transverse guide-strip, g', arranged to the 75 end of the car at or near the bottom edge.

h h are blocks, which prevent the ends of the cars themselves from coming in contact should they be brought together with too much force. It will be noticed that the outer faces 80 of the heads d round off toward the edges which form the clasping portion, the head used with one car being rounded off to the opposite side of the one on the other car. The said clasping portions are also turned in reverse 85 direction to each other and slightly beyond a right angle. This construction permits them to glance off as they strike or come in contact, and each to be caught by the other. It will be further noticed that the springs F are also 90 on reverse sides of the draw-bars of each car.

The operation is as follows: When the cars are brought together, the two draw-heads come in contact, and the draw-bars are forced aside laterally until the edges of the heads pass each 95 other, thereby compressing the spring F in its sleeve f. As soon as the rounded faces of the heads have passed each other, the said spring, by its resiliency, forces back the draw-bars, and the angular faces of the heads are brought 100 together and the coupling securely effected. As the two heads strike, the buffer-spring E allows a yielding resistance by being compressed between the metal strips e e'. When

it is desired to uncouple the cars, the operator takes hold of the lever G and depresses it, which action throws the curved shorter arm of said lever against the side of the draw-bar, thereby releasing the connection. In doing this it is only necessary to operate one of the levers.

One of the advantages in our construction of draw-head is that cars of different heights can be coupled as well as though they were all of the same height.

As shown in dotted lines, Fig. 3, we have shown the lever in a perpendicular position, which is preferable with some style of cars—15 as, for instance, "platform-cars." The bar e, that is located to the extreme end of the draw-bar, is bent around at the ends, which prevents that (the inner) end of the draw-bar from moving to either side, forming as it were a 20 pivot for the draw-bar to work upon as its other end is moved sidewise. The buffer-spring, besides lending relief to shock as the cars are brought together, also, in case the link-coupling alone is employed, serve to pre-

vent breakage of the link or pin from unsteady 25 strain in consequence of instantly yielding to the force of a sudden pull as well as the force of contact.

Having described our invention, what we claim is—

In car-couplers, the vertically-elongated heads rounded off on sides opposite to each other and having their clasping portions turned in reverse direction, said heads formed with the lips and attached at top and bottom to the 30 bands at the end of the draw-bar, in combination with said draw-bar, the springs E and F, bars e e', and the lever G, all substantially as set forth and shown.

In testimony that we claim the foregoing as 40 our own we affix our signatures in presence of two witnesses.

CHARLES A. HANGSEN.
JAMES R. COLEMAN.
